SWITCH STRUCTURE

Burton E. Shaw, Bristol, Ind., assignor to Penn
Electric Switch Co., Goshen, Ind., a corporation
of Iowa

Application February 27, 1939, Serial No. 258,707

6 Claims. (Cl. 200—83)

As one object of my present invention I provide a switch structure having a novel adjusting knob for the range of operation of the switch and an inexpensive and simple means to permit 5 auxiliary adjustment over and above that normally possible by less than 360 degree rotation of the knob.

More particularly it is my object to provide a control device such as a condition responsive 10 switch including an adjusting means that has a rotatable rod or adjusting screw, a control knob being provided for the rod and the two being normally so associated that they rotate together. The rod is capable of longitudinal movement 15 relative to the knob whereupon the knob and rod may be relatively rotated so that the rod then has a new position relative to the knob.

A further object of my invention is to provide the knob of hollow construction and the rod with 20 a head located within and thereby concealed by the knob, the knob having an internal socket to receive the head of the screw and an adjusting spring adjusted by rotation of the rod and normally tending to keep the head seated within the 25 socket.

Still another object is to provide for adjustment of the rod relative to the knob by permitting longitudinal movement of the rod for unseating the head from the socket whereupon the 30 knob and rod may be relatively adjusted and thereafter will operate through a different range as the knob is rotated from one of its limits of movement to the other.

Still a further object is to provide the knob 35 formed of a washer with a socket stamped therein and a cup-like stamping pressed over the edge of the washer for inexpensively assembling the two relative to each other after the range adjusting screw is associated with the washer and cup-like member.

With these and other objects in view my invention consists in the construction, arrangement and combination of the various parts of my device, whereby the objects contemplated 45 are attained, as hereinafter more fully set forth, pointed out in my claims and illustrated in the accompanying drawing. Although the invention is susceptible of a variety of embodiments, it is unnecessary to fully describe and illustrate 50 more than one in order to give a full understanding of the invention both from its structural and functional standpoints. Accordingly, I have illustrated a preferred and desirable embodiment of the invention in the accompanying drawing, in which;

Figure 1 is a front elevation of a switch structure embodying my invention, the cover plate therefor being removed and a portion of a bellows housing being shown in section.

Figure 2 is a sectional view on the line 2—2 of 5 Figure 1 showing parts of the structure partly omitted.

Figure 3 is an exploded perspective view of the essential elements of my invention; and

Figure 4 is an enlarged sectional view similar 10 to the upper left hand portion of Figure 2 showing the parts in position for securing auxiliary adjustment of the type peculiarly possible with my structure.

On the accompanying drawing, I have used the 15 reference numeral 10 to indicate generally a switch housing. Within the switch housing 10 I provide a switch mechanism consisting of a supporting bar 12, stationary contacts 13 and movable contacts 14. The contacts 14 are carried by an armature 15. The armature 15 is pivoted at 16 to a bracket 17 and coacts with a permanent magnet 18 to effect snap action of the switch contacts.

For automatically controlling the armature 15 25 20 I provide a bell crank lever 19 pivoted at 20 to a bracket 21 and a bellows 22. The lever 19 is operatively connected to the armature 15 by a leaf spring 23 and link elements 24 and 25. The bellows 22 is contained in a housing 26 whereby 30 the bellows is responsive to variations in pressure in the housing as produced in a tube 27 connected with the housing. Any pressure changing means may be connected with the tube 27, such as a temperature responsive capillary 35 bulb 28 in which case the tube and bulb will be charged with the proper gas or liquid to secure the desired operation in the temperature range for which the switch is designed.

An operative connection is provided between 40 the bellows 22 and the lever 19 through the medium of a thrust pin 29 connected with the head of the bellows and bearing against the bellows. A range spring 30 maintains such engagement.

The tension of the spring 30 is made adjustable in response to various positions of rotation of a rod 31. The rod 31 is threaded at 32 and these threads coact with a threaded bore of a plug 33. The plug 33 is received in the upper end of the 50 spring 30 while the lower end of the spring is provided with a hook 34 connected with the lever 19.

The adjusting rod 31 extends rotatably through a bore 35 in the casing 10 and then through a 55

washer W whereby the knob and washer are held assembled by friction. Above the washer W there is provided a head 36 adapted to seat in a socket 37 of the washer W. A knob K is positioned over 5 the head 36 and is a press-fit on the periphery of the washer W.

The knob K is inverted cup-like in character having a top wall 38 and a cylindrical wall 39. The depth of the knob K is such that the head 36 10 of the rod 31 may be left out of the socket 37 of the washer W as shown in Figure 4 whereupon the head and washer may be relatively adjusted rotationally. The socket 37 is of such shape that when the head 36 is seated therein the rod 15 31 will rotate simultaneously with the knob and washer.

The washer W may be inexpensively made as a stamping with the socket 37 stamped therein and resulting in the formation of a hub 40 on the 20 lower surface of the washer to engage the casing 10 and thereby space the major portion of the lower face of the washer from the casing. The knob K is limited to less than 360° rotation by a projection 41 therefrom to engage a stop projection 42 struck upwardly from the casing 10. 25

Practical operation

The manufacture and assembly of my switch structure are comparatively simple. The rod 31 is 30 a standard bolt instead of being made specially, which would increase the cost considerably. The elements W and K can be manufactured in great quantities as they may be stamped out. The assembly of the knob K on the washer W is a 35 simple press operation eliminating all set screws or other fastening means or welding operations. The stop 42 is easily struck up from the sheet metal casing 10 thus eliminating the making of a pin, the drilling of a hole and the mounting 40 of the pin in the hole as in usual constructions. All these features make for economy in manufacture and assembly.

The range of the switch can be adjusted at the 45 factory by utilizing a pair of pliers or suitable tool to engage the rod 31 and lift it against the constraint of the spring 30 and then rotating the knob K to a new position relative to the rod 31, if the change in adjustment is to be less than that represented by a full rotation of the knob 50 K. If several revolutions of the knob K are to be made, the knob can be lifted with the screw so that the stop elements 41 and 42 do not engage with each other.

By a combination of the two methods just 55 scribed, the switch can be preset for operation within a given range of adjustment as required by any desired installation. After the switch is installed it can be adjusted by the user throughout the range of rotation of the knob K as determined by the stops 41 and 42, but the manner 60 of adjusting the parts illustrated in Figure 4 is not obvious to the user because the head 36 and the socket 37 are concealed within the knob and the washer. A serviceman knowing the construction 65 of the switch however can at any time change the adjustment thereof so that the knob K thereafter throughout its range of movement will secure a new range of operation for the switch.

The variations in such auxiliary adjustment 70 may be made as fine as $1/12$ of a revolution due to the relative shapes of the head 36 and the socket 37 as illustrated in Figure 3.

In accordance with the provisions of the patent statutes I have described and illustrated one 75 form of my switch structure and have also dis-

closed the principle of operation thereof. I consider the form shown in the drawing to represent one of the best embodiments of the invention but desire it to be understood that the structure disclosed is only illustrative and that the invention may be carried out by other means within the scope of the appended claims. 5

I claim as new and desire to secure by Letters Patent:

1. In a switch structure, switch mechanism, condition responsive means for operating said switch mechanism in response to variations in a condition to which said condition responsive means responds and means for adjusting the range of operation of said switch structure comprising a range spring, an adjusting screw therefor, a hollow knob having limited rotation, said adjusting screw having a head enclosed within said knob, said head being other than round, said knob having an other than round socket therein 20 in which said head is normally seated, said head being unseatable from said socket by longitudinal movement of the screw against the constraint of said range spring and thereafter rotatable relative to the knob to a new position relative to said 25 socket.

2. In a control device, control mechanism, condition responsive means operatively connected therewith to change the position thereof in response to variations in the condition to which 30 said condition responsive means responds, rotatable adjusting rod and a spring effective to modify the operation of said control device in different positions of rotation of said rod, a hollow knob for effecting rotation of said rod, said rod having 35 a head within said knob, said knob having a socket to receive said head and effect rotation of the head with the knob, said spring serving to normally retain said head seated in said socket, said rod being movable longitudinally to disengage 40 said head from said socket against the constraint of said spring whereupon said knob is rotatable to a new position relative to said rod with said spring thereafter reseating said head in said socket upon release of the rod. 45

3. In a control device of the character described, control mechanism, a casing therefor, condition responsive means operatively connected with said control mechanism to change the position thereof in response to variations in a condition, an adjusting rod effective to modify the operation of said control device in different positions of rotation of said rod, a head on said rod, a washer under said head and having a socket to receive the head and prevent relative rotation of the rod and 55 washer, an inverted cup-like knob positioned over said head and connected with the periphery of said washer whereby said washer and knob completely enclose said head, the space in said cup-like knob beyond the end of said head being in 60 excess of the depth of the socket whereby to permit longitudinal movement of said rod to a position with said head out of said socket to permit rotation of said head relative to said washer, said washer having a hub on the lower surface 6 thereof, the casing of the switch having a projection and said knob having a projection to contact therewith to limit the rotation of said knob and washer. 65

4. In a control device of the character described, control mechanism, condition responsive means operatively connected therewith to change the position of the control mechanism in response to variations in the condition affecting said condition responsive means, an adjusting rod effec- 7

5 tive to modify the operation of said control device in different positions of rotation of said rod, a head on said rod, a washer under head and having a socket to receive the head and prevent relative rotation of the rod and washer, a hollow knob positioned over said head and connected with the periphery of said washer whereby said washer and knob completely enclose said head, said head being capable of movement to a position out of 10 said socket to permit rotation of said head relative to said washer and means to limit the rotation of said knob and washer.

15 5. In a control device, control mechanism, a condition responsive device operatively connected therewith to change the position of the control mechanism in response to changes in the condition responsive device, an adjusting element effective to modify the operation of said control mechanism in different positions of rotation of said 20 element, a washer having a socket, said element extending through said washer and having means coacting with said socket to prevent relative rotation of the element and washer, a hollow knob positioned over said means and connected with the periphery of said washer whereby said washer and knob completely enclose said means, the space 25 in said hollow knob beyond said means being in

excess of the depth of said socket whereby to permit longitudinal movement of said element to a position with said means out of said socket to permit rotation of said element relative to said washer and knob.

5 6. In a control device of the character described, a casing, control mechanism therein, condition responsive means operatively connected therewith to operate the control mechanism, an adjusting rod extending through a wall of said 10 casing and effective to modify the operation of said control device in different positions of rotation of said rod, a head on said rod, a washer under said head and having a socket to receive the head and prevent relative rotation of the rod 15 and washer, an inverted cup-like knob positioned over said head and connected with the periphery of said washer, the space in said cup-like knob beyond the end of said head being in excess of the depth of said socket whereby to permit longitudinal movement of said rod to a position with said head out of said socket to permit rotation of said head relative to said washer, said knob having a projection and said casing having a projection struck up therefrom to coat with said 20 25 projection of said knob and limit its rotation.
